UNITED STATES PATENT OFFICE.

WALTER K. VOORHEES AND JOHN H. OSGOOD, OF CEDAR FALLS, IOWA.

MACHINE FOR FORMING LOOPS IN WIRES.

1,073,189.

Specification of Letters Patent. Patented Sept. 16, 1913.

Application filed October 31, 1912. Serial No. 728,827.

To all whom it may concern:

Be it known that we, WALTER K. Voorhees and JOHN H. Osgood, citizens of the United States of America, and residents of 5 Cedar Falls, Blackhawk county, Iowa, have invented certain new and useful Improvements in Machines for Forming Loops in Wires, of which the following is a specification.

10 Our invention relates to improvements in machines for forming loops or eyes in wires, and the specific object of our said improvement is to devise means whereby a loop or eye may be formed and secured permanently in a wire end to adapt it for fastening the wire to some other body. This object we have accomplished by the means which are hereinafter described and claimed, and which are illustrated in the accompanying 15 drawings, in which:

Figure 1 is a plan view of our improved machine for forming loops or eyes in wires. Fig. 2 is a side elevation of said machine with the cranks removed. Fig. 3 is a front elevation of said machine, with parts broken away. Fig. 4 is a perspective detail view of the specific means employed in said machine for forming the eye or loop in the end portion of a wire, and Fig. 5 is a side elevation of said means. Fig. 6 is a perspective detail view of the operating device used to twist the end of the said wire about itself after the loop therein is formed by the other said device. Fig. 7 is a view of both said 20 devices in their relative positions assumed after forming a loop in the wire end, and immediately before twisting the wire end about itself. Fig. 8 is another position of said parts as they relatively appear when 25 the second-mentioned device has twisted the wire end once about itself, and Fig. 9 is a third position of said parts showing their relative positions at the end of the process 30 of forming the loop and securing it permanently by twisting the wire end several times about itself. Fig. 10 is a view of a piece of wire having both ends permanently looped by means of our improved machine.

Similar numerals of reference denote corresponding parts throughout the several views.

It has been found a slow and tedious process to form permanent loops or eyes in the end parts of wires by hand or with the aid 55 only of a pair of pliers, and it is to provide means for rapidly and mechanically effect-

ing this result that we present this invention. It is our intention particularly to produce such loops in the ends of wires and secure them by twisting the wire end about 60 the main body of the wire, so that the looped ends may be of a suitable and permanent form for use in wire fences or gates, or in any other location where such a construction would prove useful.

65 The machine shown is especially adapted, by reason of having two complete operating devices incorporated therein in a reversed relation, to form simultaneously loops or eyes in both ends of a relatively short piece 70 of wire. It is, of course, obvious that our invention is complete in the assemblage and use of one pair of the coöperating working devices only to form an eye or loop at a time in one end of a wire, and also that as 75 many of such pairs of devices may be located and arranged in the vicinity of each other as may be necessary or useful to form eyes or loops in as many wires ranged side by side or otherwise spaced apart in juxtaposition.

The machine shown in Figs. 1 to 3 inclusive, is one of the double type with two reversed pairs of operating devices therein as stated, and comprises a frame or supporting 85 body composed of a base 1 having an integral upright 27 supporting a flat horizontal rectangular table 2. Pairs of plates 5 and 29 of smaller dimensions and spaced apart are located on a plate 28 on the table 90 2 to leave their interspace of sufficient width to receive therein the gear-wheels 8 and 9, the lower parts of the latter descending into a hollowed out part of the plate 28. Said pairs of plates on either 95 side of said interspace are provided with cylindrical horizontal alined bearing seats adapted to receive the shaft parts 41 extending in opposite directions from and integral with the gear-wheel 9. The outer 100 ends of the bodies 41 have integral flanges 23 extending without said plates, and each provided with a detent or projection 22 having one concave face with an obliquely-directed notch 42 in its diminished extremity. Both said gear-wheel 9 and both bodies 41 are split radially and longitudinally to a point just beyond the common axis of all in order to receive the wire 24 therein which is to be operated upon, said split or groove 110 being denoted by the numerals 10 and 43. A like split or slot 25 located transversely

through the upper plate 5 is in registration and communication with the groove 43 in the other parts when said parts are rotated to have the groove open vertically upward 5 into said slot. The gear-wheel or pinion 8, which intermeshes with the said pinion 9, is secured on a shaft 13 seated rotatably in a bearing-opening in said plates 5 and 29, and which shaft has a hand-crank 14 secured 10 removably on its outer end. The plates 5, 28 and 29 are secured removably to the table 2 by means of the bolts 6 and 7, and the screws 11. The plate 28 has two relatively narrow parallel grooves 26 on its upper face located immediately along the outer sides 15 of the said plates 5 and 29 and serves to receive the disk parts 23 with their projections 22 of the shaft-bodies 41.

The ends of the plate 28 just beyond the 20 grooves 26 have vertical cylindrical orifices serving as seats for the vertical shafts 34 each having on its lower end a bevel-gear wheel as is shown at 17 and 39, and these gear-wheels both intermesh with bevel pinions 32 and 38 respectively, the latter pinions being mounted on the ends of a shaft 33 seated rotatably in a bearing-body 35 supported by an integral hanger 36 from a slide-body 3, which latter is slidably and 25 adjustably seated in a slideway formed in the table 2, and secured to said plate 28 by means of a screw or bolt 37. The shaft 33 extends to the right, and has a hand-crank 16 secured thereon removably.

Upon the upper end of each shaft 34 above the plate 28 is a rectangular body 19, shown best in Figs. 4 and 5, and which has an axial projection 21 slightly diminishing upwardly. At one side of this projection 40 and eccentric to the axis of the shaft 34 is another projection 20 extending upwardly, and which has one upper angle removed to provide a curved edge or upper end. The straight vertical opposite face of said projection 20 is cut away medially and transversely to form a groove 31 which latter is extended across the abutting face of the body 19 to provide a shelf there. Just above said groove 31 a notch 30 is provided 45 in the vertical angle of the projection 20, and which extends across the face of the projection which is opposite the projection 21. The interspace of the projections 20 and 21, when the body 19 is appropriately rocked lies in line with the groove 43 in the shaft-body 41. The outer forward corners of the uppermost plate 5 are excised to provide oblique curved surfaces 12 for a purpose to be hereinafter 50 described.

The successive stages of operation upon a wire 24 to form a loop in its end or loops in both ends, and then twist the wire ends about the body of the wire to secure the 55 loops permanently are as hereinafter de-

scribed and as shown in Figs. 7 to 9 inclusive. These figures represent the forming of a loop in one end of a wire only, but the machine above described duplicates the same process simultaneously for both ends 70 of a piece of wire of a proper length to form a tie-wire 24 such as shown in Fig. 10.

The cranks 14 and 16 are first rotated to bring the operating parts of the machine into the relative positions shown in Fig. 1, 75 and then a wire 24 is inserted in the registering grooves 10 of the gear-wheel 9, and 25 of the plate 5 and the grooves 43 of the bodies 41 to lie axially within the latter with its projecting ends received between the pairs of projections 20 and 21 on the bodies 19. The crank 16 is then rotated in an appropriate direction to cause by means of above-described gearing the bodies 80 19 to rotate sufficiently to cause the projections 20 to grasp the outer ends of said wire and bend it around the central projection 21. In the course of so bending the wire end as shown by the dotted lines in Fig. 1, is brought into contact with the inclined 85 surface 12 at the outer forward angle of the uppermost plate 5 and pushed up and back over the incline to cross above the main body of the wire. The crank 16 is then rotated oppositely far enough to bring the body 19 to the position shown in Fig. 7 to clear the projection 22 when the latter is rotating, without changing the position of the wire loop about the central projection 90 21. At this point, the crank 16 is released and the crank 14 is rotated in an appropriate direction to bring the projection 22 on the disk 23 of the body 41 into the position shown in said Fig. 7. A continued rotation of said crank in the same direction 95 causes the projection 22 to grasp the bent over end of said wire in its notch 42, whence the wire is drawn into the concavity of the face of the projection, and the projection thus holds and forces the wire end to twist 100 it about the main body of the wire as shown in Fig. 8. The rotation of the body 41 is continued sufficiently to cause said projection 22 to twist the wire end completely with a wrapping of several turns and to its 105 extremity about the body of the wire till released, as shown in Fig. 9. The moving parts are then in such a relative position that the grooves aforesaid are in registration, and the wire 24 may be lifted from them 110 clear of the machine, the conical form of the projections 21 preventing sticking. If desired some suitable device may be pivoted or otherwise connected to the machine so as to underlie the wire at some place of its length, 115 and which may be operated to lift the wire from its seat when the loops are formed and the ends twisted thereabout.

Attention is called to the notch 30 in the projection 20 of the body 19. When this 120 125 130

projection is bending the wire end about the other projection 21, the wire end in passing over the sloping surface 12 rises until caught at the top of the ascent by said notch while 5 sliding along the edge of the projection, and is held securely thereby during the remainder of the rotation of the body 19 till the loop is formed. The groove 31 permits the passage thereby of the projection 22 without interference of said bodies.

10 Having described our invention, what we claim as new, and desire to secure by Letters Patent, is:

1. A device of the class described, comprising in combination, a rotatable body having an axial projection and an eccentric projection spaced apart therefrom to receive a wire end therebetween, another body rotatable on an axis inclined toward the axis of the 15 first-mentioned body and having a diminished eccentric curved projection extending longitudinally toward the latter, and said second-mentioned body having an axial seat adapted to hold the body of said wire removably.

25 2. A device of the class described, comprising in combination, a rotatable body having an axial projection and also an eccentric projection spaced apart therefrom to receive a wire end therebetween, said eccentric projection having a notch across its inner advancing angle adapted to detachably grip said wire end in certain positions of said body, another body rotatably mounted and having its axis set at a right angle 30 to the axis of the first-mentioned body and having an eccentric projection directed toward the other body, and also provided with a longitudinal axial seat adapted to seat the body of said wire removably.

40 3. A device of the class described, comprising in combination, a rotatable body having an axial projection and an eccentric projection spaced apart therefrom to receive a wire end therebetween, another body rotatable on an axis set at an angle to the axis 45 of said first-mentioned body and having an eccentric projection extending toward the latter, said second-mentioned body having an axial opening adapted to seat the wire 50 body removably, and having on the contact face of its said eccentric projection a transverse notch adapted to grip the wire end when bent around into the path of its rotation to twist said end around the body of 55 the wire.

4. A device of the class described, comprising in combination, a rotatable body having an axial projection and an eccentric projection spaced apart therefrom to receive a wire end therebetween, another rotatable body having its axis at an angle to 60 said first-mentioned body and having a notched eccentric longitudinal projection on its end extending toward the latter, said second-mentioned body having a longitudinal 65

groove extending past its axis and serving to receive the body of said wire detachably.

5. A device of the class described, comprising in combination, a rotatable body having an axial projection and an eccentric projection spaced apart therefrom to receive a wire end therebetween, one end angle of said body being excised to leave a wire-receiving rabbet therealong, another rotatable body having its axis at an angle 70 to said first-mentioned body and having an eccentric projection extending longitudinally toward the latter, said second-mentioned body having a gear-wheel secured thereto coaxially, said gear-wheel and attached body having a longitudinal groove extending through them past the axis thereof and adapted to receive the body of said wire axially and removably, a pinion in mesh with said gear-wheel, and means for 75 rotating said pinion.

6. A device of the class described, comprising in combination, a rotatable body having an axial projection and a notched eccentric projection spaced apart therefrom to receive a wire end therebetween, said body having a gear-wheel coaxially secured to it, a pinion in mesh with said gear-wheel, means for rotating said pinion, another rotatable body set at a right angle to the first-mentioned body and having a notched eccentrically-located projection on its face directed toward the latter body and also having an axial opening adapted to removably receive the body of said wire, and independent means for rotating said second-mentioned body.

7. A device of the class described, comprising in combination, a rotatable body having an axial projection and an eccentric projection spaced apart therefrom to receive a wire end therebetween, a fixed body adjacent thereto having its upper surface inclined obliquely toward said rotatable body above the level of said wire at its uppermost part, and a rotatable body with axis set at a right angle to the first-mentioned rotatable body, and having a longitudinal groove extended thereinto past its axis to receive said wire removably, and also having an eccentric projection directed toward the first-mentioned body, said first-mentioned body having its eccentric projection adapted to engage said wire end when rotated and bend it into a loop over the body of the wire 105 by bending it moving it slidingly over and along the inclined surface of said fixed body to cross said end over the body of the wire, and the eccentric projection on the other said body being adapted when subsequently 110 rotated to engage said looped over wire end and twist it to wrap it about the wire body.

8. A device of the class described, comprising in combination, a bearing-body both transversely and longitudinally grooved, 115

and having a longitudinal orificed seat into which said longitudinal groove extends, a shaft seated rotatably in said seat and provided medially with a gear-wheel seated in said transverse groove, said gear-wheel and shaft being grooved past their axis longitudinally, a pinion in mesh with said gear-wheel, means for rotating said pinion, each end of said shaft having an eccentric projection having a concaved engaging-face, rotatable bodies seated at each end of said bearing-body in line with and spaced apart from the end of said shaft and having two projections one being axial the other eccentric thereto and spaced apart therefrom, with the interspace in line with the axis of said shaft in one position, the axes of the second-mentioned rotatable bodies being at right angles to the axis of said shaft, and means for rotating the second-mentioned bodies independently of the first-mentioned shaft, said second-mentioned bodies having

their eccentric projections adapted to grasp a wire end placed between them and said axial projections when rotated and bend it 25 toward the body of the wire into a loop, said bearing-body having its forward upper corners inclined to permit such wire end to mount thereover when being bent to pass above the plane of the wire body and cross 30 it to form an eye, and the projections of said shaft being adapted to afterward when rotated grasp said looped wire ends and twist them to enwrap them about the body 35 of the wire tightly.

Signed at Cedar Falls, Iowa, this 11th day of Oct. 1912.

WALTER K. VOORHEES.
JOHN H. OSGOOD.
